SYRINGE

Filed May 2, 1930

UNITED STATES PATENT OFFICE

WILLARD HARRIS BROCKWAY, OF NEEDHAM, MASSACHUSETTS, ASSIGNOR TO MAC-GREGOR INSTRUMENT COMPANY, OF NEEDHAM, MASSACHUSETTS, A CORPORATION OF MASSACHUSETTS

SYRINGE

Application filed May 2, 1930. Serial No. 449,182.

This invention relates to improvements in syringes and particularly syringes embodying a glass barrel within a metal holder or frame. It is desirable in such a holder to provide means for supporting the barrel and also for aligning its end or nipple with the syringe needle holder while avoiding any lateral strains on the nipple and relieving the glass barrel entirely from the thrust of the needle, thus preventing the liability of any lateral or longitudinal strain fracturing the glass barrel. My improvements are particularly adapted for use in such a syringe as that disclosed in the Warriner patent, No. 1,529,412, 15 March 10, 1925. In the drawings I have disclosed and in the specification described a form of my invention which has proven successful in practical use.

In the drawings:

Fig. 1 is a side elevation partly in section disclosing my improved structure.

Fig. 2 is a detailed vertical cross section showing a barrel end prior to alignment of the nipple with the needle connection, the aligning mechanism being in locked position.

Fig. 3 is a similar view showing the nipple in position in the bushing, the aligning mechanism being unlocked.

Fig. 4 is a detailed plan view of my rocker 20 washer, and

Fig. 5 is a side view of the same, and

Fig. 6 is a bottom plan view but with the nut removed.

In my present invention I employ the usual 35 syringe holder 1 which is provided with opposite openings 2 through which the syringe barrel may be observed. At one end the holder is provided with the usual laterally projecting finger clasps 3—3 and at its lower or needle end has a square orifice 4 through which passes the connection for the barrel and the needle. This connection comprises a bushing 5 which has a square portion 5¹ passing through the orifice 4 in the bottom of the 40 holder and extending beyond said square portion 5¹ as a threaded portion 5² adapted to be engaged by a knurled nut 6, and beneath said portion 5² terminating as a second threaded portion 5³ adapted to engage with the usual 45 syringe needle not shown. The bushing 5 is

bored as at B throughout its upper end. The bore B is adapted to receive the nipple 10¹ of the barrel 10 and thence extends as a passageway from the nipple to the needle (not shown) which is to be attached to the threaded end 5³ of the bushing 5.

Resting on the flange 1¹ of the holder 1 and encircling the square portion 5¹ of the bushing is a rocker washer 7 provided with oppositely disposed ridges 7¹ on each of its faces which permit full lateral play of the bushing 5 and tend to aid alignment of the nipple 10¹ in the bushing as hereinafter explained.

Externally of the barrel but encircling that part of the square portion 5¹ of the bushing 5 which extends beyond the orifice 4 is a second rocker washer 8 similar to the rocker washer 7 and provided with oppositely disposed ridges 8¹ on each of its faces similar to the ridges 7¹ on the rocker washer 7. This washer is held in place on the bushing by the knurled nut 6 above referred to. Additional ridges may be provided on these rocker washers 7 and 8 and the same may be variously arranged with regard to the barrel and bushing.

In operation, after the barrel 10 has been placed within the holder 1 the knurled nut 6 is unscrewed in order that full play may be given to the rocker washers 7 and 8 in order 50 that the nipple 10¹ may readily be centered in the bushing 5 without any unnecessary lateral strain on the nipple. Once the nipple 10¹ is seated in the bushing 5 the knurled nut 6 may again be tightened to hold the bushing 5 and 55 rocker washers 7—8 in rigid position with relation to the holder 1. In use, the thrust of the needle is transmitted directly through the rocker washers and bushing to the holder 1 thus entirely relieving the glass pump of any 60 lateral or longitudinal strain and avoiding the liability of fracturing the glass barrel.

Modifications will readily suggest themselves to those skilled in the art but within the scope of the present invention is claimed.

What I therefore claim and desire to secure by Letters Patent is:

1. The combination of a syringe holder having a square orifice in its lower end, a barrel in said holder, a bushing loosely mounted

in said holder and bored to receive the nipple of said barrel, said bushing extending through said orifice and constructed to secure a needle, means permitting lateral play of said bushing whereby to aid alignment of the same with said barrel comprising a pair of spaced rocker washers, one of said washers being disposed within said holder and encircling said bushing and the other of said washers encircling said bushing externally of said holder, and means for adjusting said rocker washers with relation to said bushing.

2. The combination of a syringe holder having an orifice in its lower end, a barrel in said holder, a bushing in said holder bored to receive the nipple of said barrel, said bushing extending through said orifice and constructed to secure a needle, means permitting the lateral play of said bushing whereby to aid alignment of the same with said barrel comprising rocker washers encircling said bushing, and means for adjusting said rocker washers with relation to said bushing.

3. The combination of a syringe holder having an orifice in its lower end, a barrel in said holder, a bushing in said holder bored to receive the nipple of said barrel, said bushing extending through said orifice and constructed to secure a needle, means permitting the lateral play of said bushing whereby to aid alignment of the same with said barrel comprising a rocker washer and means for adjusting said rocker washer with relation to said bushing.

4. The combination of a syringe holder having an orifice in its lower end, a barrel in said holder, a bushing in said holder bored to receive the nipple of said barrel, said bushing extending through said orifice and constructed to secure a needle, means permitting the lateral play of said bushing whereby to aid alignment of the same with said barrel, said means encircling said bushing, and means for holding the same on said bushing.

5. The combination of a syringe holder having an orifice in its lower end, a barrel in said holder, a bushing in said holder bored to receive the nipple of said barrel, said bushing extending through said orifice and constructed to secure a needle, means permitting the lateral play of said bushing whereby to aid alignment of the same with said barrel, said means encircling said bushing within said holder, and means for holding the same on said bushing.

6. The combination of a syringe holder having an orifice in its lower end, a barrel in said holder, a bushing in said holder bored to receive the nipple of said barrel, said bushing extending through said orifice and constructed to secure a needle, means permitting the lateral play of said bushing whereby to aid alignment of the same with said barrel, said means encircling said bushing external-

ly of said holder, and means for holding the same on said bushing.

7. In a syringe holder having an orifice in its lower end, a bushing adapted to seat in said orifice with lateral play, and to hold a needle and the nipple of the barrel, and means to aid alignment of said nipple with said bushing consisting of a rocker washer and means for adjusting said rocker washer to prevent or permit play thereof with relation to said bushing.

8. The combination of a syringe holder adapted to engage a barrel and provided with an orifice, a bushing adapted to seat in said orifice with lateral play in all directions and means adapted to secure said needle and the nipple of said pump barrel in alignment comprising a rocker washer and means for maintaining the same adjacent said bushing.

9. The combination of a syringe holder adapted to engage a barrel and having an orifice at one end, a bushing adapted to seat in said orifice with lateral play and means for maintaining said bushing in said orifice, a rocker washer encircling said bushing above said orifice whereby the lateral movement of said bushing is enhanced to aid alignment of said barrel in said bushing.

10. A syringe comprising a holder, a pump barrel in said holder, a bushing bored to receive the nipple of said barrel and at the other end adapted to secure a needle, means permitting lateral play of said bushing whereby to aid alignment of the same with said nipple, said means comprising a rocker washer mounted upon said bushing and means for holding the same in place thereon.

In testimony whereof, I affix my signature:
WILLARD HARRIS BROCKWAY.
